UNITED STATES PATENT OFFICE

2,592,632

APPARATUS FOR TREATING YARNS

Ollie L. Williamson, Danville, Va., assignor to Dan River Mills, Incorporated, Danville, Va., a corporation of Virginia.

Application April 23, 1948, Serial No. 22,872

5 Claims. (Cl. 118—234)

This invention relates to an apparatus for treating yarns.

Production of high strength, low stretch, high density yarns has been accomplished successfully in the prior art by a treatment of yarn with a bonding material such as disclosed, for example, in the Jennings Patent No. 2,220,958, issued November 12, 1940.

Thoroughly treating thread with moistening solution as in the Jennings patent has been difficult to accomplish, especially with heavier threads, due to the failure of the moistening solution to penetrate to the center of the thread. For best results in the aforementioned treatment, as many of the discrete fibers as possible must be first aligned and then bonded in that position. If the fibers in the center of the thread are not first treated with moistening solution, the effect of the subsequent stretching and drying is not beneficial to those particular fibers. It is well known that by squeezing a once wet yarn and rewetting the same yarn will produce a greater absorption of any given moistening solution. It is also known that a slack yarn will absorb a wetting solution or the like better than a taut yarn.

With this invention it is important to apply thoroughly a controlled amount of any desired treating solution to a thread, yarn or the like, in a continuous process characterized by a plurality of successive untensioned wettings and squeezings of each individual end, and to provide means for successive slack treatments of a yarn.

Reference is made to copending application of joint inventors Ollie L. Williamson and Howard Lee Higgins, Serial No. 15,548, filed March 18, 1948, in which a treating machine is disclosed in detail.

In the drawings:

Figure 1 is a side elevation of a machine for wetting yarn.

Figure 2 is a section on line 2-2 of Figure 1.

Referring to Figure 1, a journal arm 15 supports a spindle 20 on which is mounted a supply spool S. Above spool S is a base B on which is mounted a tank or reservoir 22. Directly beside the reservoir as shown in Figure 2, is an upright supporting arm 25 in the lower portion of which is supported a shaft 27 which projects into the reservoir 22. On the shaft is mounted a dip roll 30. A pulley 31 on shaft 27 is driven by a belt 32 from a power source in the base B. The top of the upright arm 25 is offset in a portion 34 to support a bell crank 35 which is

pivotedly mounted on the offset portion 34 by a pin 36. At the corner of the bell crank 35 is a roll 40 positioned directly above the roll 30. Spaced above the roll 40 on the vertical extension 5 of the bell crank 35 is a roll 50. Each of the rolls 40 and 50 are supported on suitable shafts

10 The horizontally extending arm 52 of the bell crank 35 has a toe portion 53 which serves to cooperate with a thumb screw 54 mounted in a swinging hook 55 on a projection 56 extending upwardly from the base B. It will be noted that the roll 40 is positioned below the pivot point 36 so that a downward movement of the extension 15 52 will cause pressure between the roll 30 and the roll 40. The roll 40 is preferably formed of a resilient material such as synthetic rubber, while the roll 30 is preferably formed of a non-corrosive material such as stainless steel. The roll 20 50 is provided with a series of spaced peripheral grooves which increase in depth from left to right as shown in Figure 2 and this roll 50 is preferably formed of material which is non-corrosive.

25 On the right hand side of base B, a spool support 60 is provided and on this support is a take-up spool T. Between the take-up spool and the roll 50 is a reciprocating guide arm 62 which may be suitably moved to insure even winding on the take-up spool.

30 To thread the machine, the thumb screw 54 is loosened to free the arm 52. This arm may then be lifted to provide clearance between rolls 30 and 40. Yarn is threaded through an eye 64 on the edge of tank 22 and then wound around 35 rolls 50 and 40 in a series of successive loops until it is taken off to the guide arm 62 and the take-up roll T. Suitable means are provided to drive the take-up T from base B but these means are not shown. After threading, the arm 52 is 40 again clamped in place by thumb screw 54 and a slight pressure applied between the rolls 30 and 40.

45 To obtain a thorough moistening of a yarn by liquid contained in tank 22, it is preferable that the yarn be repeatedly moistened and squeezed and that such yarn be in a relatively slack condition at the time of moistening. Carrying the yarn around the grooved roll 50 and the squeeze roll 40 in a plurality of loops causes multiple 50 contact of the thread at a plurality of points as it passes the driven dip roll 30. The progressively deeper grooves in roll 50 serve to create a slack condition as the thread progresses from left to right as viewed in Figure 2. Each time the thread 55 or yarn passes the roll 30, it is squeezed and also

placed in contact with additional treating material so that at once it is squeezed, dipped and slackened to insure maximum amount of pick up of the treating solutions. The treated yarn may then be taken up on roll T and transferred to further treating steps or to a point of storage.

What I claim is:

1. In an apparatus for treating thread with a liquid, a supply tank for treating solutions, a driven dip roll partially immersed in said solution, and a pair of rolls freely rotatable on axes parallel to said dip roll, one of said pair of rolls having a resilient surface in rolling contact with the dip roll, the other of said pair of rolls having a plurality of spaced peripheral grooves increasing gradually in depth from end to end, said dip roll being driven in a direction whereby a series of successive loops of thread being treated originating at the shallowest of said grooves may be passed in contact with said dip roll in varying states of decreasing tension to the deepest of said grooves.

2. In an apparatus for treating thread with a liquid, a supply tank for treating solutions, a driven dip roll partially immersed in said solution, and a pair of rolls freely rotatable on axes parallel to said dip roll, one of said pair of rolls having a resilient surface in rolling contact with the dip roll, the other of said pair of rolls having a plurality of spaced peripheral grooves increasing gradually in depth from end to end, and means for adjusting the axial relation between said dip roll and the roll in contact therewith without changing the axial relation between said pair of rolls, said dip roll being driven in a direction whereby a series of successive loops of thread being treated originating at the shallowest of said grooves may be passed in contact with said dip roll in varying states of decreasing tension to the deepest of said grooves.

3. In an apparatus for treating thread with a liquid, a supply tank for treating solutions, a driven dip roll partially immersed in said solution, and a pair of rolls freely rotatable on axes parallel to said dip roll, one of said pairs of rolls having a resilient surface in rolling contact with the dip roll, the other of said pair of rolls having a plurality of spaced peripheral grooves increasing gradually in depth from end to end, and means for adjusting the axial relation between said dip roll and the roll in contact therewith without changing the axial relation between said pair of rolls, said dip roll being driven in a direction whereby a series of successive loops of thread being treated originating at the shallowest

of said grooves may be passed in contact with said dip roll in varying states of decreasing tension to the deepest of said grooves, said last named means being arranged to effect pressure contact between said dip roll and the first roll of said pair to cause squeezing of the thread passing therebetween.

4. In an apparatus for treating thread with a liquid, a supply tank for treating solutions, a driven dip roll partially immersed in said solution, a bell crank pivoted on an axis parallel to the axis of said dip roll at a point spaced from the periphery thereof, a squeeze roll mounted on said bell crank between the dip roll and the bell crank, a tension control roll mounted in spaced parallel axial relation to said squeeze roll on said bell crank, and means for adjustably positioning said bell crank to exert pressure between said dip roll and squeeze roll.

5. In an apparatus for treating thread with a liquid, a supply tank for treating solutions, a driven dip roll partially immersed in said solution, a bell crank pivoted on an axis parallel to the axis of said dip roll at a point spaced from the periphery thereof, a squeeze roll mounted on said bell crank between the dip roll and the bell crank, a tension control roll mounted in spaced parallel axial relation to said squeeze roll on said bell crank, and means for adjustably positioning said bell crank to exert pressure between said dip roll and squeeze roll, said tension control roll having a plurality of peripheral spaced grooves of gradually increasing depth from end to end, said dip roll being driven in a direction whereby a series of successive loops around said squeeze roll and tension control roll of thread being treated originating at the shallowest of said grooves may be passed in contact with said dip roll in varying states of decreasing tension to the deepest of said grooves.
